William M. Kelly, Westfield, N. J.

Application August 15, 1941, Serial No. 406,941

12 Claims. (Cl. 101—214)

This invention relates to improvements in multi-operation printing presses employing units for collective and independent operation. More particularly, the invention relates to a two revolution flat bed press wherein a rotary unit constitutes part of the press and comprises a plate cylinder, a cooperating impression cylinder, inking mechanism, and transfer grippers. The rotary unit is so angularly arranged and positioned with respect to the impression cylinder and the bed as to provide a compact arrangement of the various press parts and mechanisms and to render the bed freely accessible. Further, the invention relates to a press of the character described wherein a bed impression cylinder rotates two revolutions in each cycle of the press to three revolutions of the rotary plate cylinder and its contacting impression cylinder. Still further, the invention relates to the provision of a delivery mechanism having gripper means for delivering the printed sheet to a swingable delivery in which the sheets are piled. The novel features of the invention will be best understood from the following description when taken together with the accompanying drawings, in which certain embodiments of the invention are disclosed, and in which the separate parts are designated by suitable reference characters in each of the views; and in which:

Fig. 1 is a diagrammatic sectional view showing parts of a press made according to my invention and indicating the general arrangement of said parts.

Fig. 1a is a diagrammatic view illustrating the gear train drive between the cylinder shafts.

Fig. 2 is a diagrammatic view illustrating the initial feed of a sheet into a press; and,

Figs. 3, 4, 5, 6 and 7 are views similar to Fig. 2 diagrammatically illustrating the various steps in the cycle of passing a sheet through the press in performing two operations thereon.

For the purpose of illustrating one adaptation of the invention, a flat bed press of the general type and kind as illustrated in my co-pending application Ser. No. 371,009, filed December 20, 1940, is illustrated in part in Fig. 1 of the drawings, slight variations being indicated in adapting the press to the multi-operating press structure forming the subject matter of this invention.

In the art, and particularly in what is known as multi-operation printing presses, rotary printing cylinders have been employed in connection with flat bed presses. In such designs, where the rotary form is impressed over the impres-

sion made by the flat bed form, they are limited to "spot" printing, that is, the rotary form must be confined to printing only in the open spaces to avoid conflict of make-ready.

Some press designs employ rotary cylinders too small to accommodate a form equal to the maximum flat form. Other efforts to do two color printing arrange rotary forms in inaccessible contact with the impression cylinder and in transfer turn the printed sheet over. To avoid "smutting" they suggest heated transfer drums.

These proposed press structures are objectionable from the standpoint of complicated press design, and inaccessibility of the working parts of the press, and particularly due to unworkable elements.

It is the purpose of my invention to provide a press employing an independent impression surface for each form; to use a two revolution impression cylinder for the flat form and a three revolution impression cylinder for the rotary form, each large enough for the maximum form; to transfer the printed sheet from one unit to the other unit printed side up to positively avoid "smutting;" to simplify the press structure, and to provide free access to all working parts, and to deliver the sheet to the delivery pile printed side up.

The invention generally speaking comprises two units, one involving a flat bed motion and the other a complete rotary motion. A press of this kind lends itself to independent operations of the flat bed as well as the rotary unit. By making the rotary cylinder demountable it also permits other operations than printing to be performed on the work sheet in its passage through the press. These presses may be constructed to perform any desired and independent function or operation upon the work sheet, including the double printing operation, which latter may be in two colors. It will also be apparent that, by tripping the ink mechanism of the rotary unit and by declutching the rotary demountable plate cylinder in any desired manner, a flat bed unit may be operated independently when a single printing operation is all that is desired, and in like manner the rotary unit may also be operated independently.

It will be understood that the diagrammatic illustration of the press in Fig. 1 of the accompanying drawings is for purposes of illustrating one adaptation and use of the invention; and in this figure 10 represents parts of the press frame; 11 represents a drive shaft driven in any desired manner. On the shaft is a gear 12 mesh-

ing with a gear 13, the latter meshing with a gear 14. Another corresponding gear 15, on shaft 15a, meshes with the gear 12. At 16 is shown one of two bed rack engaging gears. Connecting rods 17 are coupled with the gears 14 and 15 and operate mechanisms for reversing the bed 18; the bed being otherwise driven by the gears 16, engaging racks of the bed, all as is taught in said prior application.

On the shaft 19 of the gear 14 is another gear 14a located at one side of the press, which meshes with gear 20, the latter in turn meshing with gear 21 on shaft 22. On the shaft 22 is arranged an impression cylinder 23 operating in conjunction with the bed 18, an eccentric 24 being provided to move the cylinder 23 toward and from the bed as will be apparent.

At 25 is diagrammatically illustrated a main inking mechanism for the bed which is disposed at one side of the cylinder 23, and including the smoother roll 25a. At said side of the cylinder is a pivoted feed table 26 which may be swung upwardly on the pivot 27 to give access to the inking mechanism as at 25. Upon the shaft 11 is arranged a pulley 28 around which passes a belt 29, the latter passing around a pulley 30 on a shaft 31. The shaft 31 may constitute an electric motor drive shaft to actuate the shaft 11. On the shaft 15a is arranged a gear, indicated at 15b, which meshes with gear 32 on cam shaft 33. This cam shaft is utilized as a means for actuating the various eccentric and other timed mechanisms of the press which are not illustrated as they form no specific part of the present invention.

At 34 is shown part of the delivery which is arranged upon a pivot 35 to swing to one side of the machine to render the bed 18 of the press freely accessible.

Arranged slightly above and to the right of the cylinder 23, as viewed in Fig. 1 of the drawings, are two shafts 36, 37, the axes of which, with respect to the axis of the shaft 22, are arranged at a predetermined angle approximately 30° with respect to the horizontal face of the bed. This arrangement of these shafts will provide a large space or opening above the bed at this side of the press to render the bed readily accessible as will be apparent. On the shaft 36 is arranged a transfer member 38 having an eccentric 39 for moving the same toward and from the impression cylinder 23, the grippers of the member 38 being shown at 40. On the shaft 37 is arranged a rotary impression cylinder 41 having an eccentric 42 to move the cylinder 41 toward and from a rotary form cylinder 43 which is arranged upon a shaft 44, having split bearing supports for detachable mounting of said shaft. Grippers 45 are arranged at the periphery of the cylinder 41, and as customary, corresponding grippers 46 are arranged on the cylinder 23. The shafts 36, 37, 44, are driven from the shaft 22 through a gear train as diagrammatically illustrated in Fig. 1a, at the ratio of three to two; that is to say, on each two revolutions of the cylinder 23, the cylinders 40, 41, and 43 will be rotated three revolutions.

An inking mechanism 47 is provided for the cylinder 43, and suitable means may be provided for operating and tripping this mechanism as is known in the art.

Driven from the gear of the shaft 37 is a sprocket and chain delivery mechanism 48 of such length as to pick up through the medium

of grippers 49 the printed sheet as it is delivered from the cylinder 41, and to convey this sheet over the delivery pile 34, suitable mechanisms being provided to open grippers 49 when the sheet is disposed over the pile of the delivery as will be apparent.

The sprocket and chain delivery mechanism is mounted to swing about the axis 50 into a raised position as indicated in dotted lines in Fig. 1 in rendering the bed 18 accessible.

In the diagrammatic showing of Fig. 1a of the drawings, part of the gear 21 on the shaft 22 is illustrated. This gear in turn meshes with a gear 51 on the shaft 36; the gear 51 meshes with the gear 52 on the shaft 37, and the latter gear meshes with the gear 53 on the shaft 44. This establishes the fixed gear train between the shafts of the various members 23, 38, 41, and 43, in establishing the ratio of drive between the cylinders.

In Figs. 2 to 7 inclusive I have diagrammatically illustrated the passage of a worksheet 54 through the press. In Fig. 2 the worksheet is introduced between the cylinders 23—38, being picked up by the gripper 46. It might be mentioned at this time that at this particular cycle, a previously entered and finally printed sheet is being delivered from the press as indicated by the heavy dotted lines at 54a, the sheet having been picked up by the gripper 49 of the sprocket and chain delivery mechanism in feeding the worksheet over the delivery 34, upon which the sheets are piled as is indicated in part in Fig. 1 of the drawings.

In Fig. 3 of the drawings is illustrated the beginning of the printing operation upon the sheet 54, between the impression cylinder 23 and the bed 18. In this position of the cylinders, the cylinder 38 is preferably moved out of engagement with the cylinder 23, and the cylinder 41 is moved out of engagement with the cylinder 43. While the clearances provided are slight, these clearances are exaggerated in the diagrammatic illustration in this as well as the other figures. From this position, the printing operation continues as is indicated in Fig. 4 of the drawings, in which position the cylinder 38 is again moved into engagement with the cylinder 23. After completion of the printing operation, the printed sheet 54 is then picked up by the gripper 40 of the transfer cylinder 38 at the position of the cylinders as seen in Fig. 5. Thereafter, the cylinder 23 is moved upwardly out of engagement with the bed 18. The sheet is then transferred from the cylinder 38 to the impression cylinder 41 engaged by the gripper 45 of said cylinder, which position of the parts is illustrated in Fig. 6; and in this position, the cylinder 41 is moved into engagement with the cylinder 43. With the various cylinders in this last named position, the sheet 54 is passed between the cylinders 41, 43, and receives its second printing or other operation; and immediately after the position illustrated in Fig. 7, the printed sheet 54 is picked up by the gripper 49 of the delivery mechanism 48 and conveys the printed sheet over and drops it face up upon the pile of the delivery 34. During this last operation, the next successive sheet is introduced between the members 23, 38, and the above cycle of operation is repeated.

From the foregoing it will appear that immediately upon the completion of the second printing operation upon the worksheet, a new worksheet is introduced into the machine.

The particular arrangement of the various cylinders or members with respect to each other as well as the arrangement of the inking mechanisms, the feed table, and the delivery mechanisms produces in the resulting press a very practical and simple structure. In the first place, the height of the press is minimized by the relationship of the rotary plate cylinder with respect to the bed, which is made possible by the angular relationship of the members 38 and 41 with respect to the cylinder 23, and with respect to each other. Notwithstanding this latter structural arrangement, I still provide sufficient clearance above the bed to render the bed clearly accessible below the members 38, 41, as will readily appear from a consideration of Fig. 1 of the drawings. It will be noted that the work sheet in passing from the bed cylinder to the rotary cylinder is not turned over, thereby avoiding smutting. In addition to the foregoing, it will be apparent that an independent impression surface is provided for each form.

It will be apparent that the illustrations in the accompanying drawings are made diagrammatic and without regard to the particular relationship of the parts. The showing is sufficient to make the press operation clear to those skilled in the art. It is customary to arrange the gear train comprising the gears 14a, 20, 21, 51, 52, and 53, at one side of the press; and usually outwardly of the frame structure of the press, whereas the bed driving mechanism is disclosed within the frame structure of the press, and the other operating mechanisms arranged in accordance with the usual or conventional practices in press design. In view of the fact that these structures are well known in the art, the drawings have been simplified in order to more clearly emphasize the distinctive structural features of the press.

Having fully described my invention, what I claim as new and desire to secure by Letters Patent, is:

1. A printing press comprising in combination, a reciprocating bed, a two revolution impression cylinder movable toward and from the bed, the press having a feed at one end and a delivery at the other end thereof, a rotary plate cylinder arranged at the delivery end of the press entirely above said impression cylinder, a second impression cylinder arranged beneath the plate cylinder and coacting therewith, all of said cylinders having relatively fixed axes, means establishing a positive drive between said cylinders, and means conveying a sheet from the first named impression cylinder to the plate cylinder and second mentioned impression cylinder without turning said sheet over.

2. A printing press comprising in combination, a reciprocating bed, a two revolution impression cylinder movable toward and from the bed, the press having a feed at one end and a delivery at the other end thereof, a rotary plate cylinder arranged at the delivery end of the press entirely above said impression cylinder, a second impression cylinder arranged beneath the plate cylinder and coacting therewith, all of said cylinders having relatively fixed axes, means establishing a positive drive between said cylinders, means conveying a sheet from the first named impression cylinder to the plate cylinder and second mentioned impression cylinder without turning said sheet over, and said last named means comprising transfer grippers movable relatively to both of said impression cylinders.

3. A printing press comprising in combination,

a reciprocating bed, a two revolution impression cylinder movable toward and from the bed, the press having a feed at one end and a delivery at the other end thereof, a rotary plate cylinder arranged at the delivery end of the press entirely above said impression cylinder, a second impression cylinder arranged beneath the plate cylinder and coacting therewith, all of said cylinders having relatively fixed axes, means establishing a positive drive between said cylinders, means conveying a sheet from the first named impression cylinder to the plate cylinder and second mentioned impression cylinder without turning said sheet over, said delivery being swingably supported at the delivery end of the press and in spaced relation to said cylinders, and means comprising grippers arranged on an endless conveyor at the delivery end of the press for transferring a printed sheet from the second named impression cylinder to said delivery.

4. A printing press comprising in combination, a reciprocating bed, a two revolution impression cylinder movable toward and from the bed, the press having a feed at one end and a delivery at the other end thereof, a rotary plate cylinder arranged at the delivery end of the press entirely above said impression cylinder, a second impression cylinder arranged beneath the plate cylinder and coacting therewith, all of said cylinders having relatively fixed axes, means establishing a positive drive between said cylinders, means conveying a sheet from the first named impression cylinder to the plate cylinder and second mentioned impression cylinder without turning said sheet over, said delivery being swingably supported at the delivery end of the press and in spaced relation to said cylinders, and means comprising grippers arranged on an endless conveyor at the delivery end of the press for transferring a printed sheet from the second named impression cylinder to said delivery.

5. A printing press comprising in combination, a reciprocating bed, a two revolution impression cylinder movable toward and from the bed, the press having a feed at one end and a delivery at the other end thereof, a rotary plate cylinder arranged at the delivery end of the press entirely above said impression cylinder, a second impression cylinder arranged beneath the plate cylinder and coacting therewith, all of said cylinders having relatively fixed axes, means establishing a positive drive between said cylinders, means conveying a sheet from the first named impression cylinder to the plate cylinder and second mentioned impression cylinder without turning said sheet over, said delivery being swingably supported at the delivery end of the press and in spaced relation to said cylinders, and means comprising grippers arranged on an endless conveyor at the delivery end of the press for transferring a printed sheet from the second named impression cylinder to said delivery, and said conveyor means being swingable vertically to give access to the bed.

6. In a printing press, a reciprocating flat bed, a two revolution primary impression cylinder movable toward and from the bed, a three revolution rotary plate cylinder arranged at one side of and in its entirety spaced above said primary cylinder, a three revolution secondary impression cylinder arranged below the plate cylinder with the axis thereof in vertical alinement with the axis of said plate cylinder, said secondary cylinder and plate cylinder being relatively movable, said secondary cylinder being, for the most

part, arranged above and in spaced relation to the primary cylinder, a transfer member movable between the primary and secondary cylinders, all of said cylinders and the member having a fixed axes, and a gear train for rotating the cylinders at the ratio named.

7. In a printing press comprising a reciprocating flat bed with a two revolution primary impression cylinder movable toward and from the bed, a secondary impression cylinder a rotary plate cylinder arranged directly above the secondary cylinder and in its entirety above and at one side of the primary cylinder, the major portion of the secondary cylinder being arranged above the upper surface of the primary cylinder to provide at said side of the primary cylinder and above the bed a large space providing accessibility to the bed, a transfer member interposed between the primary and secondary cylinders and movable relatively thereto, and said secondary cylinder and plate cylinder being relatively movable.

8. In a printing press comprising a reciprocating flat bed with a two revolution primary impression cylinder movable toward and from the bed, a secondary impression cylinder, a rotary plate cylinder arranged directly above the secondary cylinder and in its entirety above and at one side of the primary cylinder, the major portion of the secondary cylinder being arranged above the upper surface of the primary cylinder to provide at said side of the primary cylinder and above the bed a large space providing accessibility to the bed, a transfer member interposed between the primary and secondary cylinders and movable relatively thereto, said secondary cylinder and plate cylinder being relatively movable, a delivery at said side of the primary cylinder and beyond the limit of movement of said bed, means adjacent the secondary cylinder for transferring a printed sheet therefrom to said delivery, and said last named means and the delivery being both movably supported to give access to the bed at said side of the primary cylinder.

9. In a printing press comprising a reciprocating flat bed with a two revolution primary impression cylinder movable toward and from the bed, a secondary impression cylinder, a rotary plate cylinder arranged directly above the secondary cylinder and in its entirety above and at one side of the primary cylinder, the major portion of the secondary cylinder being arranged above the upper surface of the primary cylinder to provide at said side of the primary cylinder and above the bed a large space providing accessibility to the bed, a transfer member interposed between the primary and secondary cylinders and movable relatively thereto, said secondary

cylinder and plate cylinder being relatively movable, all of said cylinders and said member having relatively fixed axes, a gear train for said axes, and inking means arranged above and in spaced relation to the primary and secondary cylinder, and cooperating with the rotary plate cylinder.

10. In a printing press, a reciprocating bed, a two revolution primary impression cylinder movable toward and from the bed, in combination with a three revolution rotary plate cylinder and a three revolution secondary impression cylinder movable toward and from the rotary plate cylinder, said secondary cylinder and plate cylinder having axes disposed in common vertical alignment and spaced to one side of the axis of the primary cylinder, and means interposed between and having an axis aligned with the axis of said primary and secondary cylinders and movable relatively to said cylinders for transferring a sheet from the primary to the secondary cylinder.

11. In a printing press, a reciprocating bed, a two revolution primary impression cylinder movable toward and from the bed, in combination with a three revolution rotary plate cylinder and a three revolution secondary impression cylinder movable toward and from the rotary plate cylinder, said secondary cylinder and plate cylinder having axes disposed in common vertical alignment and spaced to one side of the axis of the primary cylinder, means interposed between and having an axis aligned with the axis of said primary and secondary cylinders and movable relatively to said cylinders for transferring a sheet from the primary to the secondary cylinder, a delivery at said side of the primary cylinder beyond the limits of bed movement, and means comprising an endless conveyor arranged over said delivery and having grippers for transferring a printed sheet from the secondary cylinder to said delivery.

12. In a flat bed printing press, comprising a reciprocating bed, a primary impression cylinder centralized above the bed with respect to reciprocation thereof and movable toward and from said bed, said primary cylinder being rotated two revolutions in each cycle of press operation, a rotary plate cylinder arranged in its entirety above and to one side of the primary cylinder, a secondary impression cylinder arranged directly below the plate cylinder and for the major part above the upper surface of the primary cylinder, said secondary cylinder being movable toward and from the plate cylinder, and a transfer mechanism intermediate the primary and secondary cylinders and movable relatively to at least one of said cylinders.

WILLIAM M. KELLY.
